UNITED STATES PATENT OFFICE.

TOMITARO SUDZKI, OF TOKYO-FU, JAPAN.

FIREPROOF SHUTTER.

Application filed August 30, 1926. Serial No. 132,598.

This invention relates to improvements in fireproof shutters or rolling doors, and the principal object is to obtain a most effective fireproof shutter consisting of hollow slats 5 of simple construction and easily rolled up around a shaft. The other object is to provide a fireproof shutter with strong and durable slats.

The accompanying drawing shows one 10 embodiment of the invention, in which:

Fig. 1 is a front view of a part of the shutters;

Fig. 2, a side elevation partly in vertical section of the same and

Fig. 3, a sectional plan through the line 15 3—3, of Fig. 1.

As shown in the drawing, each slat consists of outer and inner plates (1) (2) having space left between them. The outer 20 plate has its upper and lower edges 3, 4 bent so as to form a channel at almost a right angle with the curved surface, edges gradually approaching each other. The ends of these edges are curled to make interlocking flanges as in (5) (6). The inner plate is bent to form a channel which 25 tightly fits into the bent portions (3) (4) of the outer plate, the upper and lower edges 7, 8 being bent at almost a right angle with the curved surface, the distance 30 between them gradually diverging.

As stated above, the outer plate (1) being in a shape of trapezoidal channel spreading at the bottom, and the inner plate also in 35 the same shape but narrowing at the bottom, they will be tightly interlocked with each other and form a hollow slat if the latter is slipped into the former from its one end and then the bent portions (3) (4) of the outer plate are pressed on the bent portions 40 (7) (8) of the inner plate. Thus, the inner plate (2) does not separate from the outer plate, even if not connected to the latter by riveting or like means. However, in this 45 shutter like an ordinary one, it is necessary to attach an end lock or shield to both ends to prevent lateral movement of each slat, so that it is advisable to ensure the connection of the outer and inner plates still more 50 perfectly by utilizing the rivet which connects the end lock with the slat. In the drawing, (9) is an end lock which covers the end of the slat, especially the end of the in-

terlocking joint. Its body (10) is provided with a tubular projection (11), the height of 55 which is made equal to the width of space between the slats, namely a space between the outer and inner plates. The rivet (12) that passes through the said projection to connect the said end lock with the slats is 60 used also for connecting the two plates. The outer surface of the end lock is made convex at as (13) to enable the slats to move up and down smoothly along rails. The 65 air space between the outer and inner plates is intended for the prevention of heat effectively, and this space may sometimes be filled with heat insulating materials. The shutter of my invention is very effective 70 against fire and can be rolled up around a shaft without difficulty. Besides, it can be manufactured easily. An ordinary slat consists of a surface curving gradually between upper and lower interlocking flanges, while in this invention these flanges being bent at 75 almost the right angle with the curved surface as in (3) (4), the slat is more rigid.

Claims:

1. A fire-proof shutter consisting of slats jointed together, each slat comprising outer 80 and inner plates having space left between them, both plates being bent obliquely at the upper and lower edges to form a channel having widened bottom and a channel having widened top respectively and interlocked with each other, both plates having air 85 space between them, the edges of the outer plate being extended laterally and curved whereby to be jointed to the correspondingly shaped edge of an adjacent slat of the shutter. 90

2. A fire-proof shutter consisting of slats jointed together, each slat comprising outer and inner plates having space left between them, both plates being bent obliquely at 95 the upper and lower edges to form a channel having widened bottom and a channel having widened top respectively and interlocked with each other, the edges of the outer plate being extended laterally and curved 100 whereby to be jointed to the correspondingly shaped edge of an adjacent slat of the shutter.

In testimony whereof I have affixed my signature.

TOMITARO SUDZKI.
